AUTOMATIC LIFTING MECHANISM

Paul C. Grunwell and Arthur H. Nolan,
St. Louis, Mo.

Application July 30, 1941, Serial No. 404,586

6 Claims. (Cl. 61—28)

(Granted under the act of March 3, 1883, as
amended April 30, 1928; 370 O. G. 757)

This invention described herein may be manufactured and used by or for the Government for governmental purposes, without the payment to us of any royalty thereon.

This invention relates generally to hoisting apparatus, but more particularly to a hoisting device provided with an improved mechanism for automatically picking up a load and releasing the same when it is lowered upon a supporting surface.

The pick-up mechanism as herein described is particularly adaptable for use with cranes for the placing of bulkheads in locks and dams, but it may also be used in handling any object where an automatic pick-up and release mechanism is required.

One object of the device is to provide a simple, easily operated, and ruggedly constructed automatic handling device for raising and lowering bulkheads and for releasing the same at the bottom of their guideways.

Another object of the invention is to provide a pick-up and release device of this character which may be actuated beyond the vision of the operator and which is entirely automatic in operation.

With these and other objects in view, this invention consists in certain novel details of construction, combination and arrangement of parts to be more particularly hereinafter described and claimed.

Briefly stated, the invention comprises a lifting beam adapted to be raised, lowered and transported by a crane, coupling members connected to said beam and adapted to automatically engage and disengage complementary coupling members attached to a bulkhead, and a manually controlled mechanism coacting with the beam-carried coupling members to automatically effect their engagement or disengagement with respect to the coupling members associated with the bulkhead.

Referring more particularly to the accompanying drawings in which corresponding parts are indicated by similar reference characters:

Fig. 1 is a perspective view of a lifting beam coupled to a bulkhead, the beam and bulkhead being partially sectionized to show the construction of the coupling members and the control mechanism associated therewith;

Fig. 2 is a perspective showing an assembly of an engaging hook and the control mechanism associated therewith, and adjustable couplings;

Fig. 3 is a partially sectionized view showing

the beam and bulkhead with the hook being moved into engaging position;

Fig. 4 is a view similar to that shown in Fig. 3, with the hook in engaged position;

5 Fig. 5 is a view similar to that shown in Fig. 3, with the hook being moved in to disengaging position;

Fig. 6 is a view similar to that shown in Fig. 3, with the hook in disengaged position;

10 Fig. 7 is a perspective view showing a hook in conjunction with a modified form of segmental ratchet formed independent of the hook; and

Fig. 8 is a diagrammatic view showing a modified form of the device in which the hooks are connected by links to toothed segments to effect simultaneous movement thereof.

Referring to Fig. 1 it will be noted that the apparatus comprises a pair of latch or lifting hooks 10 and 10' keyed to a common shaft 11 which is rotatably mounted at the center of gravity of a beam 14, the latter being suspended from a crane (not shown) by the cables 15 and 15' and adapted to be lowered upon the top of a bulkhead 16.

20 25 The shaft is formed in two sections 50 and 51 united by a coupling 52, including relatively adjustable flanges 53 and 54. The flanges 53 and 54 are formed with an equal number of holes equally spaced on circles of equal radii so that they will register with each other when the flanges are brought together. With this construction the sections 50 and 51 of the shaft may be relatively adjusted until the hooks 10 and 10' attached thereto are brought into simultaneous engagement with pick-up lugs 24 and 24' and the flanges 53 and 54 are connected to retain the hooks in their adjusted position by bolts 55.

30 35 In this connection it is to be understood that other adjusting means other than that just described may be used when such use is deemed necessary.

40 45 The latch hook 10 is provided with a segmental ratchet 17 which is formed with ratchet teeth 18 extending over a portion of the segment and an arcuate cam surface 19 extending at the level of the top of the teeth 18 to an arcuate extremity of the segment. The hooks 10 and 10' are provided with laterally extending brackets 20 and 20' to each of which a guide pin is pivotally attached. The pins project through openings in brackets 22 and 22' projecting from transverse walls 23 and 23' located within the frame structure of the beam 14. The pins are surrounded by springs 21 and 21' which abut the brackets 50 55 22 and 22' and thereby tend to move the hooks

into engaged position with respect to pick-up lugs 24 and 24' attached to the bulkhead. These pick-up lugs are provided with upper and lower cam surfaces or ramps 26, 26' and 27, 27' respectively, which will be further described in the description of the operation of the device.

A pawl actuating spring 28 is mounted on a pin pivotally connected to the pawl 29 and projecting through an opening in the bracket 22. The pawl spring abuts the pawl and the bracket 22 and tends to move the pawl into engagement with the segmental ratchet 17. The pawl 29 is fulcrumed towards its center and adapted to engage the teeth 18 of the ratchet 17, and to slide over the cam surface 19 of the segmental portion of the hook.

In order to control the movement of the pawl 29 from the end of the beam 14 a link 30 is connected to the pawl 29, the other end of link 30 being pivotally attached to a bell crank lever 31 mounted on the beam 14. The bell crank 31 is connected through another link 32 to a lever 33 also mounted on the beam and the lever 33 is in turn connected with a setting lever 34 which may be locked in either of two positions by engagement with a ratchet 35, the engaging members consisting of a locking lever 36 connected with a link 37, one end of said link 37 being adapted to project within either of the grooves 38 or 39 in the ratchet 35.

Instead of forming the segmental ratchet 17 integral with the hook 10, it may be formed as a separate unit 17' which is fastened to the shaft 11, as shown in Fig. 7.

To prevent horizontal movement of the beam 14 with respect to the bulkhead 16 guide members 41 and 41' are attached to the beam 14 and project downward therefrom for engagement with the lugs 24 and 24' as shown in the drawings.

To pick up the bulkhead in the storage yard, the pawl setting lever 34 is raised to notch 38. This raises pawl 29 from ratchet 17 and allows hooks 10 and 10' to move without restriction. The device is then lowered over the bulkhead 16, as shown in Fig. 3. Hooks 10 and 10' strike the top ramps 26 and 26' on lugs 24 and 24'. The weight of the beam 14 on the ramps 26 and 26' forces the hooks 10 and 10' and shaft 11 to rotate, compressing springs 21 and 21', thereby passing top ramps 26 and 26'. Horizontal movement of the device is prevented by guides 41 and 41' engaging the back of lugs 24 and 24'. The device is lowered until beam 14 rests on bulkhead 16, thus causing the hooks to contact lower ramps 27 and 27' and be again rotated as shown dotted in Fig. 3. When the lifting cables show slack to the operator the downward travel of the device is complete, and the device can then be raised. Springs 21 and 21' force the hooks to follow up the lower ramp and into engagement with stirrups 40 and 40', as shown in Fig. 4. The bulkhead is now suspended on the latch hooks, ready for transportation to a desired location.

After the bulkhead is raised to its carrying position, pawl setting lever 34 is lowered to notch 39. This in turn lowers pawl 29 to the cam surface 19 of ratchet 17. The bulkhead and device is placed in the desired pier slots located on the upstream side of the dam and is lowered until the bulkhead strikes sill 42, as shown in Figs. 5 and 6, or a previously placed bulkhead. The weight of the beam forces hooks 10 and 10' down the bottom ramps 27 and 27' of lugs 24 and 24', forcing the hooks 10 and 10' and shaft 11 to

rotate, thus permitting pawl 29 to engage with the teeth 18 in ratchet 17, which prevents springs 21 and 21' from forcing the hooks 10 and 10' back into engagement with the latching lugs 24 and 24'. When beam 14 strikes bulkhead 16 and the lifting cables show slack to the operator, the unlatching operation is complete, and the beam can then be raised, leaving the bulkhead in a desired position.

10 To remove the bulkheads 16 from the slots in the dam, the same sequence of operation as described above for "Pickup of bulkheads at the storage points" is used.

15 In the modified form of the device shown in Fig. 8, the lifting hooks 60 and 60' are pivotally mounted at right angles to the longitudinal axis of the frame 14' and are connected by drag links 61, 61' and 62, 62' to pivotally mounted intermediate toothed segments 63, 63', which couple the hooks for simultaneous movement to effect engagement and disengagement of the pick-up lugs. The hook 60 is provided with a segmental ratchet 64 of similar construction as the segment 17, and which is engaged by a pawl, (not shown) in the same manner as explained above and illustrated in Figs. 1 to 7. The control mechanism and the operation of hooks 60 and 60' is similar to that of hooks 10 and 10', the only difference being the direction of their 20 pivotal axis and the manner of connecting them for simultaneous movement.

Having described my invention, what I claim as new and wish to secure by Letters Patent is:

1. An automatic pick-up and release mechanism comprising a lifting beam, a shaft mounted longitudinally within said beam, lifting hooks keyed to said shaft and adapted to engage complementary coupling members comprising lugs provided with upper and lower ramps, attached 25 to a bulkhead, springs connected with said hooks adapted to retain the same in a position for coupling engagement with said lugs, a segmental cam member provided with a ratchet attached to said shaft, a pawl pivotally connected to said beam, a spring adapted to move said pawl into engagement with said cam member, and a manually operated control means, including a setting lever 30 adapted to retain said pawl from engagement with said cam to permit the free movement of said hooks to engage the upper ramp of said complementary coupling members on said bulkhead, and to release said pawl for engagement with said cam by the action of said cam spring and to allow said hooks to be moved out of engagement 35 with the complementary coupling members by contact with the lower ramps thereon and to be retained in said position to effect release of the bulkhead from the beam.

2. An automatic pick-up and release mechanism comprising, a lifting beam, aligned sectional shafts mounted longitudinally within the beam, coupling means for the shaft sections, hooks keyed to the respective shaft sections, a bulkhead, means for connecting the lifting beam to the bulkhead, said means including lugs formed with upper and lower ramps, adapted to be engaged by said hooks, springs connected with said hooks adapted to retain the same in a position for coupling engagement with said lugs, a segmental cam member provided with a ratchet attached to said shaft, a pawl pivotally connected to said beam, a spring adapted to move said pawl into engagement with said cam member, and a manually operated control means, including a setting lever 40 adapted to hold said pawl out of engagement with

said cam to permit the free movement of said hooks to engage the upper ramp of said complementary coupling members on said bulkhead, and to release said pawl for engagement with said cam by the action of said cam spring and to allow said hooks to be moved out of engagement with the complementary coupling members by contact with the lower ramps thereon and to be retained in said position to effect release of the bulkhead from the beam.

3. An automatic pick-up and release mechanism comprising, a lifting beam, aligned sectional shafts mounted longitudinally within the beam, coupling means for the shaft sections, said coupling means including relatively adjustable flanges, hooks keyed to the respective shaft sections, a bulkhead, means for connecting the lifting beam to the bulkhead, said means including lugs formed with upper and lower ramps adapted to be engaged by said hooks, springs connected with said hooks adapted to retain the same in a position for coupling engagement with said lugs, a segmental cam member provided with a ratchet attached to said shaft, a pawl pivotally connected to said beam, a spring adapted to move said pawl into engagement with said cam member, and a manually operated control means, including a setting lever adapted to hold said pawl out of engagement with said cam to permit the free movement of said hooks to engage the upper ramp of said complementary coupling members on said bulkhead, and to release said pawl for engagement with said cam by the action of said cam spring and to allow said hooks to be moved out of engagement with the complementary coupling members by contact with the lower ramps thereon and to be retained in said position to effect release of the bulkhead from the beam.

4. An automatic pick-up and release mechanism including a lifting beam, spring-pressed lifting hooks pivotally mounted on said beam and adapted to engage and disengage lug members mounted upon bulkheads, said lug members being provided with upper ramps having stirrups adapted to be engaged by said hooks on lowering

- 5 the beam to loading position, and lower ramps adapted to move said hooks out of engaging position with respect to said stirrups on lowering the beam below loading position, and means including an arcuate ratchet connected to said hooks and a manually controlled pawl pivotally connected to said beam for automatically effecting the retention of said hooks from engaging position and thereby effect clearance of the stirrups on elevation of the beam and release of the bulkhead.
- 15 6. An automatic pick-up and release mechanism including a lifting beam, lifting hooks pivotally mounted on said beam and adapted to engage and disengage lug members mounted upon bulkheads, said lug members being provided with upper ramps having stirrups adapted to be engaged by said hooks on lowering the beam to loading position, and lower ramps adapted to move said hooks out of engaging position with respect to said stirrups on lowering the beam below loading position, and means for automatically effecting the retention of said hooks from engaging position and thereby effect clearance of the stirrups on elevation of the beam and release of the bulkhead.
- 20 7. An automatic pick-up and release mechanism including a lifting beam, lifting hooks pivotally mounted on said beam and adapted to engage and disengage lug members mounted upon bulkheads, said lug members being provided with upper ramps having stirrups adapted to be engaged by said hooks on lowering the beam to loading position, and lower ramps adapted to move said hooks out of engaging position with respect to said stirrups on lowering the beam below loading position, and means for automatically effecting the retention of said hooks from engaging position and thereby effect clearance of the stirrups on elevation of the beam and release of the bulkhead.
- 25 8. An automatic pick-up and release mechanism including a lifting beam, lifting hooks pivotally mounted on said beam and adapted to engage and disengage lug members mounted upon bulkheads, said lug members being provided with upper ramps having stirrups adapted to be engaged by said hooks on lowering the beam to loading position, and lower ramps adapted to move said hooks out of engaging position with respect to said stirrups on lowering the beam below loading position, and means including a ratchet connected to said hooks and a manually controlled pawl pivotally connected to said beam for automatically effecting the retention of said hooks from engaging position and thereby effect clearance of the stirrups on elevation of the beam and release of the bulkhead.
